DISPLAY STAND FOR AN OUTBOARD MOTOR OR THE LIKE

Elmer C. Kiekhaefer, Cedarburg, Wis.

Application March 30, 1955, Serial No. 35,291

Term of patent 14 years

(Cl. D80—9)

FIG. 1.

FIG. 2.

FIG. 3.

Fig. 1 is a side perspective view of a display stand for an outboard motor showing my new design;

Fig. 2 is a rear elevation view of the display stand shown in Fig. 1; and

Fig. 3 is a plan view of my display stand.

The broken lines shown in Fig. 1 are for illustrative purposes only.

I claim:

The ornamental design for a display stand for an outboard motor or the like, as shown and described.
